UNITED STATES PATENT OFFICE

2,008,227

ATTACHMENT FOR WIRE STRANDS

Frank Ward Reilly, Chattanooga, Tenn.

Application August 12, 1933, Serial No. 684,888

1 Claim. (Cl. 24—123)

This invention relates to attachments and fittings for stranded wire structures.

The primary object of the invention is to provide an attachment or fitting whereby the stranded wire structure will be firmly secured in the attachment or fitting by what can best be termed a wavy kinked or crimped association, such wavy kinked or crimped association being obtained in the present invention without any appreciable or undue constriction of the wire stranded structure.

Another object is to provide a fitting, or attachment, which, when subjected to the pressure required for anchorage of the inserted cable or other wire structure, will itself be permanently molded or formed by said pressure into its ultimate or final cross-sectional shape.

With these and other objects in view, the invention consists in certain details of construction and combinations and arrangements of parts, all as will hereinafter be more fully described and the novel features particularly pointed out in the appended claims.

In the accompanying drawing:

Fig. 1 is an elevational view of an attachment or fitting made in accordance with the present invention but before it has been secured to a stranded wire structure;

Fig. 2 is an end view of the attachment illustrated in Fig. 1;

Fig. 3 is a view similar to Fig. 1, but partly in section, showing a stranded wire structure inserted within the attachment;

Fig. 4 is a view similar to Fig. 3 illustrating the attachment after it has been compressed to crimp the stranded wire structure whereby the latter is secured in the attachment;

Fig. 5 is an elevational view showing a modified form of the invention;

Fig. 6 is an end view of the attachment shown in Fig. 5;

Fig. 7 is a sectional view of the modified form of attachment with the stranded wire structure inserted therein;

Fig. 8 is a similar view of the stranded wire structure secured in the fitting by crimping;

Fig. 9 is a transverse sectional view on the line 9—9 of Fig. 8.

The term "stranded wire structure" as used herein designates a plurality of wires laid together in a spiral form about a common longitudinal axis, forming a simple strand, or a plurality of such strands laid together in a spiral form about a common longitudinal axis to form a multiple strand wire rope structure. In the lat-

ter case, the center portion of the structure may be formed of non-metallic material, fiber centers often being used in wire rope structures. These various formations or arrangements of a multiplicity of wires, or strands, are the general products of wire rope manufacturers of today.

As shown in Figs. 1 to 4, the attachment comprises a sleeve-like portion, having an axial bore 10 therein and external protuberances 11 preferably arranged throughout substantially the entire length of the sleeve-like portion. In this form of the attachment, the protuberances 11 are in the form of an open or spaced helical rib, with the valley, or depression, between two juxtaposed raised portions of the rib at any point on the exterior of the sleeve being disposed opposite a raised portion at a point diametrically opposite such valley or depression. In other words, the protuberances disposed longitudinally of the sleeve at any point on its surface are staggered with respect to the protuberances at a diametrically opposite point on the surface of the sleeve. At one end the sleeve portion merges into a suitable formation for attachment, or connection, with other members. In the attachment shown in Figs. 1 to 4, this end is in the form of a cleved end portion 12.

It will be observed that the bore within the sleeve portion is straight and disposed coincident with the axis of the sleeve, so that a stranded wire structure 13 may be readily inserted therein, as shown in Fig. 3. In applying, or securing, the attachment on a stranded wire structure the latter is inserted in the bore 10 and, then, suitable pressure applied to the exterior of the sleeve, under which circumstances, the irregularities on the sleeve, in this instance, the helical rib, will be transferred, so to speak, to the wall of the bore 10 with the result that a crimping action is imposed upon the stranded wire structure. In other words, the deformations originally on the exterior of a sleeve are transferred to the interior of the sleeve, but, as the irregularities are staggered with respect to each other at opposite sides of the sleeve, there is secured a crimping, or the formation of undulations, in the stranded wire structure as distinguished from the formation of appreciable constrictions or any appreciable compression of the stranded wire structure. At the same time the exterior of the sleeve is reduced to its final or ultimate cross-sectional shape.

As just pointed out, there is no constriction, or substantial reduction of a stranded wire structure in the present fitting, and, therefore, there

is not imparted to said structure any high radial pressure. This distinction between crimping and any considerable reduction in the diameter of the stranded wire structure is important, because, where the stranded wire structure is constricted, the reduction in diameter results in the various wires being deformed at the point of contact with other wires. In ordinary wire strand construction, the successive layers of wires are frequently wound in opposite spiral directions with the result that wires in successive layers cross each other at an angle. Therefore, when a high radial pressure is applied to such a wire structure, the wires are forced into each other at their points of contact and, as a result, the individual wires suffer a reduction in cross-sectional area. Consequently, there is a reduction of strength. On the other hand, where the original irregularities of the exterior of the sleeve are staggered with respect to one another, and the transfer of these irregularities to the interior of the sleeve does nothing more than form crimps, or undulations, in the stranded wire structure without any appreciable radial pressures being set up in said structure, these difficulties just outlined are eliminated.

In the form of attachment shown in Figs. 5 to 9, the irregularities, or undulations, 11, originally formed on the exterior of the sleeve-like portion of the attachment are arranged in a single plane, so to speak, transversely of said sleeve-like portion. This is clearly shown in Fig. 6. Described somewhat more in detail, the modified form of attachment comprises the irregularities 11 on the exterior of the sleeve-like portion, the raised portions constituted by said irregularities being disposed opposite the dished portions at diametrically opposite sides. The bore 10 coincides with the longitudinal axis of the sleeve-like portion, affording easy insertion of the

stranded wire structure 13. After the stranded wire structure is inserted in the bore 10, necessary pressure is applied to the exterior of the attachment, so that the projections 11 are transferred to the interior and deform the stranded wire structure, as shown in Fig. 8. In this instance, one end of the attachment is provided with a threaded socket 14 for attachment of any member that is to be connected thereto.

It will be appreciated, of course, that the stranded wire structure may extend through only a partial length of the attachment, or the entire length thereof and, also, that the fitting may be applied intermediately upon the stranded wire structure for the purpose of forming a stop or the like. The extent of crimping should also be regulated, or determined, by a minimum sound wall thickness between the longitudinal bore and the outer periphery of the sleeve-like portion.

While attachments embodying my invention have, by reason of effecting anchorage by undulation rather than constriction, especial utility and advantage when used on stranded wire structures, they are by no means restricted to use thereon but are applicable to other structures such as single strand wire and flexible rods. I therefore claim my invention broadly, as indicated by the appended claim.

An attachment for anchored installation upon wire structures such as stranded wire cable and the like, said attachment having a malleable metallic body portion provided with an axial bore for receiving the cable or the like, and having an integral external rib of helical form the pitch of which is such as to provide a complementary helical indentation 180 degrees displaced with respect to said helical rib.

FRANK WARD REILLY.
